UNITED STATES PATENT OFFICE.

PERRY BROWN AND WILLIAM TRABUE, OF LOUISVILLE, KENTUCKY; SAID TRABUE ASSIGNOR TO DANIEL E. DOHERTY, OF SAME PLACE.

VICE.

SPECIFICATION forming part of Letters Patent No. 380,178, dated March 27, 1888.

Application filed April 4, 1887. Serial No. 233,547. (Model.)

To all whom it may concern:

Be it known that we, PERRY BROWN and WILLIAM TRABUE, both citizens of the United States of America, residing at Louisville, in the county of Jefferson and State of Kentucky, have invented certain new and useful Improvements in Vises, of which the following is a specification, reference being had therein to the accompanying drawings, in which—

10 Figure 1 is a perspective side view of our vise; Fig. 2, a central vertical longitudinal section; Fig. 3, a perspective view of the movable jaw, screw, and nut; and Figs. 4, 5, and 6 are details which will be more fully referred to hereinafter.

This improvement relates more particularly to that class of vises in which the movable jaw may be rapidly moved to adjust it approximately to the size of the work, and in which 20 a screw is used for clamping it when so adjusted; and the invention consists in the peculiar construction, arrangement, and combination of parts, hereinafter more particularly described, and then pointed out in the claims.

25 Referring now to the details of the drawings, A represents the fixed jaw of the vise, in which works a slide, B, (see Fig. 5,) having on its under side a rack, C, and carrying with it a nut or female screw, D, which is preferably 30 fitted into a slot, b, in the lower part of the slide and fastened there by a pin, d. The movable jaw E has its slide F fitted to pass within the slide B, and is slotted, as shown in Fig. 3, to allow it to pass on each side of the nut D.

35 At G is shown the screw, which is fitted and secured to the movable jaw in the ordinary manner, and is provided with the usual handle, g.

Fitted in a recess in the lower part of the fixed jaw is a rocking dog, H, having a portion cut away, as shown at h, and provided with a pin, h', which bears against one end of a spring, I, set in a curved recess, as shown in Fig. 2. At one end of the dog is a handle or lever, H', by which the dog can be turned into 40 the position shown by dotted lines in Fig. 2.

We deem it important that the slide F be bifurcated or recessed to receive the nut D, inasmuch as this enables us to make the vise much more compact than where the nut is located outside of the slide, as has been proposed.

If the vise is to be made to swivel, we provide the lower side of the fixed jaw with a base, J, having corrugations j on a supplementary plate, K, provided with holes, through which may be passed screws or bolts L, to secure the same to a bench, M. Attached to the center of base J is a screw-bolt, N, which passes through the center of plate K, and is provided with a wing-nut, O, by screwing up which the base, plate, and bench are firmly secured together. It is obvious that by loosening said wing-nut the base, and consequently the vise, of which it forms a part, may be turned in any desired position, and by screwing up the nut again it may be secured in said position. On 55 the opposite ends of the slide B are a pin, P, and lug Q, which act as stops to prevent the slide moving too far in either direction.

The operation of the vise being obvious from the above description it is therefore unnecessary to give any detailed description of the same, and it will suffice to say that by turning the handle H' and dog H into the position shown in dotted lines in Fig. 2 the movable jaw E and slide B can be readily and rapidly 60 moved in either direction, so as to allow of the placing of any desired article between the jaws, and by allowing the spring I to act upon the dog the latter is turned, as shown in full lines in Fig. 2, so as to catch in the rack C and hold 65 the slide B fast, where, by turning the handle g and screw G, the article between the jaws will be clamped fast, as with the ordinary vise.

From the above it will be seen that we have produced a vise that will not only have the ordinary screw-grip—so essential for some styles of work—but one which can be rapidly adjusted to the different sizes of articles to be clamped therein, and which will, owing to the slide B, open much wider than the ordinary 70 screw-vises.

Having thus shown one way of carrying out our invention, but without limiting ourselves to the exact construction shown, we claim as new—

1. The combination of the fixed jaw of a vise and the screw thereof with a movable jaw having a bifurcated or recessed slide, an intermediate slide independently connected with said movable and fixed jaws, and a nut for the screw, 75 80 85 90 95 100

connected to the intermediate slide and entering the recess in the fixed jaw, substantially as described.

2. The combination, with the fixed jaw A and the movable jaw E, having a bifurcated slide, F, of the screw G, turning in said jaw E, the slide B, receiving the slide F of the movable jaw, the nut D, fixed in the slide B and entering the recess in the slide F, and the dog 10 H, catching in a rack on the slide B, substantially as described.

3. The combination, with the fixed jaw A and the movable jaw E, having a bifurcated slide, F, of the screw G, turning in said jaw 15 E, the slide B, provided with a rack on its un-

der side and constructed to receive the slide F of the movable jaw, the nut D, fixed in a slot in the slide B and adapted to pass into the bifurcation of the slide F, the dog H, catching on the rack on the slide B, and the spring I, acting on the dog, substantially as described. 20

In testimony whereof we affix our signatures, in presence of two witnesses, this 30th day of March, 1887.

PERRY BROWN.
WILLIAM TRABUE.
